(57) **CLAIM**

The ornamental design for a vertical cable manager, as shown and described.

DESCRIPTION

FIG. 1 is a front perspective view of a vertical cable manager, incorporating the new design;
FIG. 2 is a front view of the vertical cable manager of FIG. 1;

FIG. 3 is a top view of the vertical cable manager of FIG. 1, the bottom view being a mirror image of the top view;
FIG. 4 is a right side view of the vertical cable manager of FIG. 1, the left side view being a mirror image of the right side view;

FIG. 5 is a front perspective view of the vertical cable manager of FIG. 1 with the door open; and,

FIG. 6 is a front perspective view of a vertical cable manager, incorporating the new design.
